METHOD AND APPARATUS FOR SORTING
FRUITS AND VEGETABLES

Roy M. Magnuson, Campbell, Calif.

Application May 28, 1948, Serial No. 29,733

16 Claims. (Cl. 146—224)

1

The present invention relates to the sorting of fruit and vegetable articles by shape and is concerned more particularly with a sorting method and apparatus which can be selectively operated to retain objects of a given shape while rejecting objects of an irregular or a different shape. In the automatic processing of fruits and vegetables one of the troublesome factors is the presence in a given lot of irregular and uneven shapes which do not adapt themselves to the automatic processing machinery. For example, in the positioning of articles such as onions, apricots and peaches for halving, regularly shaped objects of a group adapt themselves well to automatic operation while the irregular shapes tend to be improperly positioned and as a result are not halved properly. Also, in processing different types and different shapes the mechanism when adjusted to process properly one particular shape of object will not work efficiently with another shape, and the entire operation becomes more economical if each piece or object can be fed to the proper processing station.

Accordingly, it is a general object of this invention to enable sorting of articles of fruit and vegetable character by their shape.

A further object of the invention is to provide sorting apparatus of an automatic character which will enable retention of a selected shape of object and reject other shapes.

A further object of the invention is to provide apparatus of the above character in which each article is sorted individually while at the same time providing for sorting of a large number of articles within a given time so as to be capable of use in production operations.

Other objects and advantages of the invention will be apparent from the following description of a preferred embodiment of the invention, as illustrated in the accompanying drawings, in which:

Figure 1 is a schematic plan view of apparatus embodying the invention.

Figure 2 is a schematic side elevational view of the apparatus shown in Figure 1.

Figure 3 is an enlarged side elevational view of the sorting roll structure of the invention.

Figure 4 is a fragmentary plan view of the sorting roll structure.

Referring to Figures 1 and 2, the general apparatus includes a hopper 10 from which the articles to be processed are fed over an inspection belt 11 and thence to a series of sizing rolls 12 of conventional construction. Articles of the selected size fall between the rolls 12 to a discharge

chute 13 and are discharged onto a conventional form of shuffle feed device 14 which operates to deliver rows of articles at its discharge end. The discharge chute 16 of the shuffle feed leads to the sorting roll structure 17 of the instant invention and is timed to deliver a row of articles to each pair of sorting rolls. Associated with the sorting structure 17 is a transverse discharge belt 18 which receives the rejected articles while the articles retained are carried over the discharge end of the sorting roll structure.

Referring to Figures 3 and 4, the sorting roll structure includes respective pairs of idler sprockets 21 and drive sprockets 22 about which respective chains 23 are trained, only one each of sprockets 21 and 22 and chain 23 are seen in Figure 3. The chains 23 support a series of pairs of sorting rolls 26 and 27, the pairs of rolls being spaced apart to provide discharge spaces for rejected articles. Each pair of rolls 26 and 27 provides a series of sorting pockets which are spaced axially of the rolls to receive a row of articles from the shuffle feed mechanism 14 so that there will be one article in each pocket as indicated in dotted lines at 28 in Figure 4. Preferably each sorting pocket provides a three-point support for the article in the pocket and for this purpose the roll 26 of each pair is formed with a series of V-shaped grooves 29. The rolls 26 and 27 of each pair are driven at a differential speed which can be adjusted and for this purpose each of the rolls 26 carries at one end a pulley 31 which is engaged by a V-belt 32 running within a guide 33 and trained about a drive pulley 34 on a drive shaft 36. As seen in Figure 1, the shaft 36 is connected to and driven by a conventional form of variable speed motor 37. Similarly, the rolls 27 (at the end opposite to the pulley ends of the rolls 26) are provided with drive pulleys 38 engaged with a V-belt 39 and driven through a drive pulley 41 from a variable speed motor 42 (Figure 1). Both of the belts 32 and 39 have spring-urged idler pulleys 43 associated therewith for slack take-up.

I have discovered that articles of the character referred to herein have rotative stability when freely supported and turned at a number of revolutions per minute within a particular speed range which is related to the shape and regularity of shape of the articles. Also, if the speed of rotation is outside of the range for a particular article, the articles have a rotative instability and will eject themselves from the sorting rolls. With fruits the rotative stability is generally achieved with a fruit rotating about its root-stem axis.

However, with some fruit, for example, apricots, a condition of stability can also be achieved at a higher speed range in which the fruit rotates on its greatest diameter, i. e., on its diameter containing the suture.

In general it is the upper limit of a speed range which enables the selective sorting of articles of the above character as all articles will remain on the rolls at low speeds and as the speed is raised to increase the R. P. M. of the articles, various shapes, either regular or irregular, will reach a speed at which they are unstable and will be bounced or rolled from the supporting rolls.

In the sorting of onions by shape, for example, I have found that the speed range for stability of torpedo-shaped onions is sufficiently lower than for round or flat onions and that the torpedo-shaped onions can be sorted from the round or flat-shaped onions by operating the rolls to provide an R. P. M. of the torpedo-shaped onions above their rotative stability range so that these onions are rejected while flat or round onions will be retained on the rolls. Also, flat onions will be rejected in a low speed range in which round onions are stable on the rolls, while round onions are rejected at higher speeds at which flat onions are stable. In each case (with the exception of perfectly symmetrical articles) a more or less critical rejection of articles can be made by controlling the speed of rotation of the objects on the rolls. Also the degree of irregularity (i. e., weight unbalance) within a given shape of onion which will be rejected can be controlled by controlling the speed range to provide the proper R. P. M. of the articles. In general, the higher the speed of the onion, the greater the requirement for uniform weight distribution to have rotative stability on the rolls.

In connection with the use of this apparatus and in employing the sorting method disclosed herein, it is desirable to first perform a sizing operation by diameter so that the articles such as onions carried onto the sorting rolls are within a size range which can be brought to substantially the same R. P. M. by operation of the sorting rolls so that irregular shapes within this size will be rejected. However, if desired, a sorting by size can also be effected on the same type of rolls as the speed range of the rolls which will give rotative stability to a small onion of a given shape and will not give rotative stability to a large onion of the same shape, and vice versa.

In making a particular sort, the speed of operation of the respective sets of rolls 26 and 27 are selected with reference to the particular shape and size of onion which is to be progressed and the sizing roll structure 12 is similarly selected to pass the selected size through for processing in the sorting structure. As a specific example, using three and three-quarter inch diameter rolls with the grooves of the grooved roll having an included angle of 120°, and working with onions of from two to two and one-half diameters, successful rejection of irregular shapes from round onions was obtained with an R. P. M. of both rolls of about 225 giving a surface speed of the rolls of 221 feet per minute. It will be noted that while the surface speed of the full diameter of the grooved roll is the same as that of the smooth roll, the effective surface speed of the grooved roll on the article is less because the article is supported in the groove at a roll portion of less than full diameter.

The sorting roll structure itself is preferable such as to provide a differential speed relation

between the rolls with the leading roll turning faster than the following roll. Where pockets providing triangular support are employed, it is preferable that the grooved roll be in trailing position. It will be appreciated that the differential speed relation between the rolls can be carried out using the same R. P. M. of the rolls by providing different surface characteristics, for example, having one roll rough and one smooth so that the amount of slippage, in effect, gives the differential speed. Also, this differential effect can be obtained by mounting one roll at a slightly higher elevation than the other so that the lower roll has a better traction driving effect with respect to the articles being sorted.

The sorting method can be carried out with plain rolls and with feeding of the articles longitudinally of the rolls by virtue of differential rotation thereof. However, the pocket forming rolls are considered preferable for feeding a row of objects to processing apparatus requiring a timed feed of the objects because the pockets prevent endwise progression of the articles along the rolls due to the differential action of the turning and supporting rolls and the weight unbalance of the articles themselves.

With the machine operation, the onions or other articles of irregular shape which are supported in the pockets of the roll structure will be 30 rotatively unstable and will be displaced from the pocket to fall between the pairs of rolls onto the discharge belt 18. Those articles for which the speed range is proper to give rotative stability will be carried with the rolls to the discharge 35 end of the sorting roll structure and if desired, for example, can be fed directly into a halving and slicing arrangement of the character shown in my copending application Serial No. 587,124, filed April 7, 1945, for Onion Handling and Cutting Apparatus and Method.

Referring to Figures 5 and 6, there is illustrated an apparatus embodying the instant invention in which the roll structure passes through three successive zones in connection with the sorting, inspection and halving of the fruit or vegetable article. There is shown schematically a shuffle-type feeder 14 from which the rows of articles are transferred by a rotary transfer device 51 having pockets to receive the rows of fruit from the shuffle feeder and to transfer them in properly timed relation to the roll structure. In the present instance the roll structure in each case is made up of a series of spaced apart pairs of rolls, and each pair of rolls 26 and 27 are of the construction previously described except that each roll 27 is provided with a series of peripheral slots 52 in alignment with the apex of the V-shaped groove in the adjacent roll 26. The peripheral slots 52, as later described, provide clearance for the halving knives.

While the rolls are passing through a sorting zone indicated generally at 53, the rolls are driven at the desired selected differential speeds by means of a belt and pulley structure 54 positioned above the rolls and engaging pulleys 56 on the respective supporting shafts of the rolls 27. Each roll 26 is driven through a belt and pulley arrangement 57 from the cooperating roll 26. As previously described, the operation of the rolls 26-27 in this sorting zone 53 is for the purpose of ejecting the articles which will not position properly on the rolls and such ejected articles fall onto the transverse conveyor 18 to which suitable deflecting plates 58 lead. After the rolls 75 pass out of the influence of the drive 54 they

enter an inspection zone 59 in which the rotation of the rolls stops and the articles in the pockets in the rolls can be inspected for proper positioning or for defects in the articles, etc. With certain articles it may not be desirable to stop the rotation of rolls during inspection and, if desired, suitable drive means may be provided to operate the rolls at a reduced speed during inspection. In this zone the workers may manually position articles which are not properly positioned for halving, but were not within the character of articles ejected in the sorting zone 53. It will be noted that conveyor 18 and one deflecting plate 58 extend under the inspection zone to receive any manually rejected articles.

After the rolls travel through the inspection zone 59 they enter the halving zone 61 wherein the rolls are again rotated through an overhead pulley and belt structure 62 at selected differential speeds of the type desirable to effect positioning of the articles for halving. The correct range of speed for positioning for halving operation is not necessarily the same as the proper rejection speed. Near the end of this halving zone the articles in each pocket encounter a halving knife 63 pivoted in a suitable fashion at 64 to float with respect to the rolls 26-27 and the fruit or other articles thereon. The operation of the floating knives 63, for example, in connection with apricots, is to cut through to the pit of the apricot so that the apricot halves will fall apart and in most cases the pit is also freed.

After halving, the halved articles travel over the discharge end of the roll structure onto a suitable conveyor 66. The respective drive arrangements 54 and 62 are preferably provided with a conventional variable drive of the type indicated in connection with the form of the invention shown in Figures 1-4.

While I have shown and described a preferred embodiment of the invention, it will be apparent that the invention is capable of further variation and modification and its scope should be limited only by the scope of the claims appended hereto.

I claim:

1. The method of sorting fruits and vegetables according to shape which comprises supporting the lower portions of the articles at a plurality of spaced points, applying a rotative effect in the same direction relative to the horizontal axes of the articles at each point but at different speeds, thereby spinning the articles about said axes and removing unstable articles from said supporting position.

2. The method of sorting fruits and vegetables according to shape which comprises supporting the lower portions of the articles at a plurality of spaced points, applying a rotative effect in the same direction relative to the horizontal axes of the articles at each point, thereby spinning the articles about said axes, whereby articles of a certain shape will stably spin in contact with said points, and articles of other shapes will develop instability which results in their being removed from said supporting position.

3. The method of sorting fruits and vegetables according to shape which comprises supporting the lower portions of the articles at a plurality of spaced points, conveying the articles supported at such spaced points past a first discharge zone to a second discharge zone, applying a rotative effect in the same direction relative to the horizontal axes of the articles at each of said spaced points but at different speeds to rotate the articles at a selected speed at which speed articles of a

selected shape will have rotative stability and articles of other shapes will have rotative instability, thereby causing retention of articles of said selected shape for discharge at the second discharge zone while articles of other shapes will be ejected during travel of such articles past the first discharge zone.

4. The method of sorting fruits and vegetables according to shape and halving the articles, which comprises supporting the lower portions of the articles at a plurality of spaced points, conveying the articles supported on such points through successive sorting, inspecting and halving zones, applying a rotative effect in the same direction relative to the horizontal axes of the articles at each point but at different speeds as the articles move through said sorting zone to cause retention of articles of a selected shape which have a stable rotative condition at the speed of rotation of the articles passing through the sorting zone, supporting the articles at said spaced points without rotation of the articles while being conveyed through the inspection zone, and applying a relative effect in the same direction relative to the horizontal axes of the articles at each of said spaced points to rotate the articles as they move through said halving zone, and halving the articles.

5. The method of sorting fruits and vegetables according to shape and halving the articles, which comprises supporting the lower portions of the articles at a plurality of spaced points, conveying the articles supported on such points through successive sorting, inspecting and halving zones, applying a rotative effect in the same direction relative to the horizontal axes of the articles at each point but at different speeds as the articles move through said sorting zone to cause retention of articles of a selected shape which have a stable rotative condition at the speed of rotation of the articles passing through the sorting zone, supporting the articles at said spaced points while being conveyed through the inspection zone, and applying a rotative effect in the same direction relative to the horizontal axes of the articles at each of said spaced points to rotate the articles as they move through said halving zone, and halving the articles.

6. The method of sorting fruits and vegetables according to shape and halving the articles, which comprises supporting the lower portions of the articles at a plurality of spaced points, conveying the articles supported on such points through successive sorting, inspecting and halving zones, applying a rotative effect in the same direction relative to the horizontal axes of the articles at each point as the articles move through said sorting zone to cause retention of articles of a selected shape which have a stable rotative condition at the speed of rotation of the articles passing through the sorting zone, supporting the articles at said spaced points while being conveyed through the inspection zone, and applying a rotative effect in the same direction relative to the horizontal axes of the articles at each of said spaced points to rotate the articles as they move through said halving zone, and halving the articles.

7. In a machine for sorting fruits and vegetables according to shape, a series of pairs of rolls with adjacent pairs of rolls spaced apart to provide discharge openings for rejected articles, the rolls of each pair providing an article supporting valley therebetween and at least one roll of each pair being grooved circumferentially to

provide article supporting pockets along the valley, and means driving the respective rolls of each pair in the same direction at selected differential speeds to effect discharge of rejected articles upwardly over one roll of a pair and into one of said discharge openings.

8. In a machine for sorting fruits and vegetables according to shape, an endless series of pairs of rolls with adjacent pairs of rolls spaced apart to provide discharge openings for rejecting articles, the rolls of each pair providing an article supporting valley therebetween and at least one roll of each pair being grooved circumferentially to provide article supporting pockets along the valley, means for supporting and moving said series of pairs of rolls from the feed end to the discharge end of the machine, and means driving the respective rolls of each pair in the same direction at selected differential speeds to effect discharge of rejected articles upwardly over one roll of a pair and into one of said discharge openings.

9. In a machine for sorting fruits and vegetables according to shape, an endless series of pairs of rolls with adjacent pairs of rolls spaced apart to provide discharge openings for rejected articles, the rolls of each pair providing an article supporting valley therebetween and one roll of each pair having V-shaped grooves to provide article supporting pockets along the valley, means for supporting and moving said series of pairs of rolls from the feed end to the discharge end of the machine, and means driving the respective rolls of each pair at selected differential speeds to effect discharge of rejected articles upwardly over one roll of a pair and into one of said discharge openings.

10. In a machine for sorting fruit and vegetable articles according to shape, a series of pairs of rolls with adjacent pairs of rolls spaced apart to provide discharge openings for rejected articles, the rolls of each pair providing an article supporting valley therebetween, and means driving respective rolls of each pair in the same direction at selected differential speeds to effect discharge of rejected articles upwardly over one roll of a pair and into one of said discharge openings.

11. In a machine for sorting fruit and vegetable articles according to shape, an endless series of pairs of rolls with adjacent pairs of rolls spaced apart to provide discharge openings for rejected articles, the rolls of each pair providing an article supporting valley therebetween, means for supporting and moving said series of pairs of rolls from the feed end to the discharge end of the machine, and means driving the respective rolls of each pair in the same direction at selected differential speeds to effect discharge of rejected articles upwardly over one roll of a pair and into one of said discharge openings.

12. In a machine for processing fruit and vegetable articles, an endless series of pairs of rolls with adjacent pairs of rolls spaced apart to provide discharge openings therebetween, the rolls of each pair providing an article supporting valley therebetween and at least one roll of each pair having grooves to provide a series of article supporting and sorting pockets along the valley, means for supporting and moving said series of pairs of rolls from the feed end to the discharge end of the machine through successive sorting, inspecting and halving zones, drive means for said rolls in said sorting zone to effect rotation of the rolls of each pair at selected differential

speeds to eject articles of an undesired shape, drive means for said rolls in said halving zone to effect rotation of the rolls of each pair at selected differential speeds, and halving means in said halving zone.

13. In a machine for processing fruit and vegetable articles, an endless series of pairs of rolls with adjacent pairs of rolls spaced apart to provide discharge openings therebetween, the rolls of each pair providing an article supporting valley therebetween and at least one roll of each pair having a groove to provide an article supporting and sorting pocket in the valley, means for supporting and moving said series of pairs of rolls from the feed end to the discharge end of the machine through successive sorting, inspecting and halving zones, drive means for said rolls in said sorting zone to effect rotation of the rolls of each pair at selected differential speeds to eject articles of an undesired shape, drive means for said rolls in said halving zone to effect rotation of the rolls of each pair at selected differential speeds, and halving means in said halving zone.

14. In a machine for processing fruit and vegetable articles, an endless series of pairs of rolls with adjacent pairs of rolls spaced apart to provide discharge openings therebetween, the rolls of each pair providing an article supporting valley therebetween and at least one roll of each pair having V-shaped grooves to provide a series of article supporting and sorting pockets along the valley, means for supporting and moving said series of pairs of rolls from the feed end to the discharge end of the machine through successive sorting and halving zones, drive means for said rolls in said sorting zone to effect rotation of the rolls of each pair at selected differential speeds to eject articles of an undesired shape, drive means for said rolls in said halving zone to effect rotation of the rolls of each pair at selected differential speeds, and halving means in said halving zone.

15. In a machine for processing fruit and vegetable articles, an endless series of pairs of rolls with adjacent pairs of rolls spaced apart to provide discharge openings therebetween, the rolls of each pair providing an article supporting valley therebetween and at least one roll of each pair having a V-shaped groove to provide an article supporting and sorting pocket in the valley, means for supporting and moving said series of pairs of rolls from the feed end to the discharge end of the machine through successive sorting and halving zones, drive means for said rolls in said sorting zone to effect rotation of the rolls of each pair at selected differential speeds to eject articles of an undesired shape, drive means for said rolls in said halving zone to effect rotation of the rolls of each pair at selected differential speeds, and halving means in said halving zone.

16. In a machine for processing fruit and vegetable articles, an endless series of pairs of rolls with adjacent pairs of rolls spaced apart to provide discharge openings therebetween, the rolls of each pair providing an article supporting valley therebetween, means for supporting and moving said series of pairs of rolls from the feed end to the discharge end of the machine through successive sorting and halving zones, drive means for said rolls in said sorting zone to effect rotation of the rolls of each pair at selected differential speeds to eject articles of an undesired shape, drive means for said rolls in said halving zone to effect rotation of the rolls of each pair at selected differential speeds to eject articles of an undesired shape, drive means for said rolls in said halving

zone to effect rotation of the rolls of each pair at selected differential speeds, and halving means in said halving zone.
